United States Patent Office.

STEPHEN W. WALKER, OF ANSON, MAINE.

Letters Patent No. 65,778, dated June 11, 1867.

IMPROVEMENT IN HORSE-RAKES.

The Schedule referred to in these Letters Patent and making part of the same.

TO ALL WHOM IT MAY CONCERN:

Be it known that I, STEPHEN W. WALKER, of Anson, in the county of Somerset, and State of Maine, have invented an Improvement in Wooden Teeth Horse-Rakes; and I do hereby declare that the following, taken in connection with the drawings which accompany and form part of this specification, is a description of my invention sufficient to enable those skilled in the art to practise it.

The invention relates to that class of horse-rakes having straight wooden teeth attached to heads or bars which swing loosely and independently on a shaft or bar running parallel to and generally a little above the axle-tree of the wagon. These implements are generally known under the name of the "Delano Horse-Rake," and I believe form the subject of the United States Letters Patent No. 6,151, of February 27, 1849, granted to C. Delano.

In said Delano construction, and such modifications of the same as have been heretofore made, the tooth is always attached to its head or bar by a rigid connection, so that the position or angle of each tooth with respect to the bar is fixed and determined, there being no capability of yield in the tooth itself. Such construction or arrangement, however, is defective in that it is often desirable that a tooth should yield easily in an upward direction, or without having to lift the head or bar to which it is attached, as when passing over undulating ground or against slight obstructions; and the object of my invention is to make provision for such direct movement or yield of each tooth or set of adjacent teeth, to accomplish which I hinge each tooth or set of teeth to the lower end of the head or bar, and apply a spring just inside of this hinge, such springs, while holding the teeth in normal position, allowing each set thereof to yield upwardly with respect to the head or bar, and it is this construction which constitutes my invention.

In carrying out such construction I prefer to arrange the teeth in series, with three or four teeth to each set, as I find the teeth operate more advantageously upon the hay or grass, where three or four are connected and move together, than when each tooth is independent from the other teeth in its action. I therefore represent in the drawings one set of teeth with the head or swing-frame to which they are attached, a series of these frames placed side by side, and swinging on a common shaft, making up, with the wagon, the whole rake, the general arrangement and mode of operation, aside from my invention, being not unlike the Delano rake, to which reference has been made.

A denotes a plan and B a side view of a set of teeth applied to the swing-frame in accordance with my invention. *a a a a* denote four wooden teeth connected together by a rod, *b*, and making up one set of the series, the rear end of the teeth entering a rocker-shaft, *c*, having journal-pins, which turn freely in bearings *d*, at the lower end of the frame or head *e*, the upper end of which frame is so applied as to swing freely on the horizontal rod mounted over the wagon axle-tree. From the connecting-rod or bar *b* a rod, *f*, extends upwards and loosely through a cross-piece, *g*, of the frame *e*, this rod having a screw cut upon its upper end, upon which screw a nut, *h*, plays, and having beneath this cross-piece, a spring *i*, one end of which bears against the under surface of the cross-piece, while the other end bears against the head of a fork in the screw-rod, the stress of the spring tending to keep the teeth in normal position relatively to the frame *e*, the angle of the teeth to the frame being determined by the nut *h*. Now it will be obvious that while the teeth are thus held normally in position by the spring and nut, each set of teeth yield readily to any unevenness in the surface of the ground over which they operate without having to lift the frame *e*, and without liability to stick or catch in such uneven surface. Each individual tooth may be applied in this manner, but I consider the arrangement shown to be preferable.

I claim the combination of the frame *e*, rods *f*, springs *i*, and teeth *a*, arranged and operating substantially as described.

S. W. WALKER.
